BLANK FEEDING AND POSITIONING MECHANISM FOR CAN BODY MAKING MACHINES

Filed June 17, 1927

2 Sheets-Sheet 2

UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF DELAWARE.

BLANK FEEDING AND POSITIONING MECHANISM FOR CAN-BODY-MAKING MACHINES.

Application filed June 17, 1927. Serial No. 199,465.

This invention relates to improvements in can body-making machines, and particularly to that portion of such machines wherein a blank having previously formed marginal hooks is positioned tangent to a horn about which such blank is wrapped, the marginal hooks being then interlocked and the side seam thus formed, swedged down to form a secure seal. The present invention more particularly relates to means for moving the blank into position and accurately securing it in such position.

One object of the present invention is to provide an improved gripper finger whereby the blanks are moved from one position to another, where successive operations are performed upon them.

A further object is to provide an improved means for positively positioning the blanks with respect to the horn about which such blanks are bent to form the hollow can body.

Other objects and special features of the invention will be set forth in the following description, throughout which reference is had to the accompanying drawings, wherein

Figure 1 is a fragmentary side elevation partially in section of the gripper finger according to the present invention, the gripper finger being shown in its open, or released position.

Fig. 2 is a plan view of the device shown in Fig. 1.

Fig. 3 corresponds to Fig. 1 except that the gripper finger has been moved to its opposed position, and in which position the blank is positively gripped between the jaws of the finger.

Fig. 4 is a cross-section taken along the line IV—IV of Fig. 3, the section being taken as viewed from the left.

Fig. 5 is a cross-section taken along the line V—V of Fig. 3, the section being viewed from the right.

Fig. 6 is a small scale view corresponding to Fig. 1, but shows diagrammatically successive gripper fingers whereby the blanks are moved to successive stations.

Fig. 7 is a central and vertical longitudinal cross-section taken through the horn about which the blanks are wrapped, and illustrates the improved mechanism for holding the

blank in position while it is being bent around the horn.

Fig. 8 is a fragmentary plan view of the mechanism illustrated in Fig. 7.

Fig. 9 is a transverse cross-section taken along the line IX—IX of Fig. 7, this view illustrating only the horn and the member which co-operates with it to hold the blank in position during the body-forming operation.

Fig. 10 is a fragmentary cross-section taken along the line X—X of Fig. 7.

The improvements herein set forth, though applicable to a variety of mechanisms, are particularly designed for use in a can body-making machine having the general characteristics of the can body-maker described in United States Patent No. 1,081,050, granted to me December 9, 1913, and reference may be had to such patent for a more detailed explanation of the general construction and co-operative relationship of the several co-acting elements in a can body-making machine.

According to the present invention, improved and more positive acting blank-gripping devices are provided to take the place of the gripper-fingers illustrated in my prior patent above referred to, particularly in Figs. 3 and 4. The present improved blank-gripping device is herein illustrated in Figs. 1 to 6 inclusive, and referring to these figures, this portion of the mechanism will now be described.

Upon a table or platform 1, which usually provides the support or mounting for the several devices which cooperate to form a sheet metal blank into a completed can body, is guided a pair of reciprocatory feed bars 2. These bars carry a plurality of blank-gripping devices generally referred to by the letter A, the function of which is to carry the blanks forwardly upon each successive forward movement of the feed bars 2 to the next advanced position or station so that the

blanks are caused to progress through the machine step by step, different operations being performed upon the blanks in the several positions to which they are brought. In the usual can body-making machines these successive operations comprise (1) notching of the corners of the blanks; (2) bending the

marginal hooks, which eventually are brought together to form the side seam of the can body; and (3) wrapping or bending the blank around the horn to form the tubular body, at which station the marginal hooks are then interlocked and bumped or pressed together to form the usual lock seam. The process of thus forming can bodies is continuous, and with the modern automatic sheet feeding mechanism, together with mechanical improvements according to the present invention, the speed at which the blanks are converted into can bodies runs above 300 per minute. At such speed it is highly important that the action of the several component parts of the mechanism be as nearly positive as possible, and to this end the present gripper-fingers are provided with positive mechanical locking means whereby the blank is gripped as between the jaws of a vise, instead of as heretofore being held between the lips of a spring clip, such as the device illustrated in my prior patent to which reference has hereinbefore been made.

25 The improved blank-gripping device comprises upper and lower finger-like members 5, 6 respectively, these members being pivotally mounted at their left-hand end, and providing at their right-hand end jaws 7, 8. The jaws may be caused to separate to receive the sheet metal blank by means of a spring 9 interposed between the members 5, 6, spring-retaining recesses 10 being provided to hold the spring in position.

35 The finger members are mechanically brought together to positively grip the blank, which they engage upon a forward movement of the feed bar 2, by the action of a link or yoke 11 pivotally connected to the upper finger member 5. Such pivotal connection is suitably provided by means of a pin 12 which extends through said member and opposite sides of the link, the two sides of which embrace both the upper and lower finger members, as indicated in Figs. 1 and 2. The two sides of the link or yoke 11 are connected below the gripper fingers by a pin 13 upon which is mounted a roller 14, the said roller cooperating with the curved lower face 15 of the bottom finger member to draw the finger members together when the yoke is shifted from the position shown in Figure 1 to that shown in Fig. 3. The contour of the curved surface 15 is preferably designed so that over 50 approximately the first half of the movement of yoke 11 from right to left the jaws of the gripper finger will be caused to positively engage the blank; and thereafter a continuation of such movement merely preserves the grip thus obtained. This is accomplished by providing over the further range of movement along surface 15 a uniform radius with respect to the pivotal axis of the yoke. The engagement and release of the gripper finger 65 jaws through the actuation of yoke 11 is ac-

complished in a manner which will hereinafter be described. The pivotal mounting at the left-hand end of the gripper fingers is conveniently provided by rounding the upper and lower surfaces of the members 5, 6 so that they bear smoothly upon a central pin 20 and are freely housed within the cylindrical recess 21 in the feed bar 2. The ends of pin 20 are preferably provided with flanges 22 which serve to accurately align the upper and lower finger members which bear against the said pin. The upper portion of feed bar 2 which serves to retain the pivoted end of the gripper device in position, comprises a removable block 23 which is imbedded flush with the face of the bar. This block is held in position by screws 24.

The feed bar is recessed, as shown in Figs. 1 to 5 inclusive, and provides an opening at the top through which the upper jaw 7 of the gripper-finger projects, and an opening at the bottom through which the lower end of yoke 11 and roller 14 downwardly project. Between a ledge 25 formed in the part of the feed bar immediately below the right-hand end of the gripper-finger, a spring 26 is mounted, such spring serving to normally hold the upper jaw of the gripper-finger above the surface of the guide bar. The gripper-finger is checked accurately in this upper or normal position by the under surface 27 of block 23, against which it is urged by the action of the spring.

35 The yoke-like link or actuator 11 which controls the movement of the gripper-finger jaws, in one position, locking them securely to grip a sheet of metal between them, and in another position releasing said jaws so that a sheet may be freely slipped between them, is itself controlled by lugs 30, 31 which are secured in a channel 32 formed in the table 1 immediately below the path of movement of the gripper-finger. The lower end of the yoke or gripper actuator 11 carrying roller 14, projects into channel 32, so that upon a movement to the left, as indicated in Fig. 1, the roller will be engaged by lug 30 and swung to the right about the yoke pivot 12, thereby running off the "high" portion of curved surface 15 and falling into the portion of such surface lying to the right, where the lesser radius about pivot 12 permits the lower member 6 to drop away from the upper member 5 under the action of spring 9, and thereby opening the blank-gripping jaws 7, 8.

When the reciprocatory feed bar 2 is moved to the right, roller 14, at the lower end of the gripper-finger actuator 11, will engage lug 31, and the further movement of the feed bar to the end of its stroke will shift the gripper actuator to the position indicated in Fig. 3, thus locking the jaws 7, 8 of the gripper-finger securely upon the sheet metal blank B.

In the particular embodiment described, it is only necessary to cause the locking or re-

lease of the gripper-finger toward the two extremes of its reciprocating movement with the feed bar 2; that is to say, as the feed bar approaches its extreme position to the left, the lug 30 is engaged by roller 14 and the jaws of the gripper device are thereby opened, and the jaws remain in such open position until the reverse movement of the feed bar carries the gripper device almost to its extreme right-hand position, where roller 14 engages the lug or trip member 31 and shifts the actuator 11 to the left, thereby locking the jaws together. Obviously, if it were desired to effect a locking or release of the gripper jaws at other positions, this could be readily accomplished by positioning trip members, such as lug 30, at other points along the path of movement of the gripper device, and certain of such lugs could be so formed that after they had been engaged by the roller which controls the movement of the jaws and had moved such roller to the jaw-releasing position, for example, the roller would freely pass over the lug. In order that the lugs 30, 31 may be readily replaced, adjusted or shifted to different positions, they are preferably formed with a flat base portion 33 which may be readily fastened at any desired position along the table 1 by means of screws 34.

As shown in Fig. 6, the blanks B are fed onto the left-hand end of feed bars 2, the blanks being first engaged by the hook or knife edge 35. The blanks are preferably fed automatically by a feed device similar to that illustrated in my said prior Patent No. 1,081,050. The forward movement i. e., to the right in Figs. 1 and 6, first carries a blank underneath the top blank-guiding strips 36. The weight of these strips is sufficient to frictionally hold the blank upon the surface of the table so that it will not be displaced upon the rearward movement of the feed bars which carry the gripper-fingers beneath the blank, bringing such fingers to rest immediately to the rear of the blank which has been delivered to the first position beneath the guide strips 36. The jaw 7 of the gripper device, which normally projects above the surface of the reciprocating feed bars, is depressed when the gripper device is moved rearwardly underneath the blank, the upper inclined surface 37 of such jaw engaging the edge of the blank beneath which it passes, thereby throwing the gripper nose flush with the surface of the feed bar, the spring 26 yielding to permit such downward movement. Immediately upon coming out from under the blank, spring 26 causes the gripper-finger to assume its normal position with the upper jaw 7 thereof projecting above the feed bar, so that when such bar starts forward, the gripper jaws are open and in a position to readily engage the blank, which now lies immediately in front of them. The nose portion of the

gripper jaws is preferably rounded, as shown, so that if a blank should not lie perfectly flat upon the table, it will, nevertheless, be guided into the jaws upon a forward movement of the feed bar.

At points where it is desired to accurately position the blanks, blank-stripping pawls 40 are provided, such pawls being pivotally mounted upon a fixed part of the mechanism and tensioned by means of a spring 41 so that they tend to drop behind each blank when the blank is moved forwardly. The feed bar having reached its extreme right-hand position, starts on its backward stroke, bringing the blank which has been positively gripped by the closure of gripper-finger jaws 7, 8 into contact with pawl 40. The grip of the jaws, while of considerable force, is not sufficient to prevent the stripping of the blank from between them as the feed bar continues its rearward movement, so that the blank, after being brought securely into contact with the stripping pawls (the pawls being preferably arranged in pairs one at either side of the blank) is freed from the jaws. Thus the blank is positively positioned and with great accuracy, even at very high operating speeds. The continued rearward movement of the feed bar is sufficient to bring the next succeeding pair of gripper-fingers beneath the blank which has been brought to a definite position of rest in the manner described, and to cause such gripper-fingers to emerge at the rear edge of the blank, the upper jaws 7 thereof springing upward to engage the rear edge of the blank immediately upon the next forward movement of the feed bar. This cycle is repeated as many times as necessary, at each reciprocation of the feed bars one pair of gripper-fingers passing the blank on to a position of rest, where, upon a subsequent cycle of movement, the blank will be engaged by the next succeeding pair of gripper-fingers and again advanced. As the gripper-fingers move forward, the jaws are preferably designed to exert little, if any, frictional effect upon the blank between them, such gripping effect not being necessary because the blank is simply pushed ahead to its advanced position by engaging the vertical shoulder 42 formed at the rear of the active gripping surface of jaw 7. Before the feed bar has reached its most advanced position, the jaws are brought into engagement with the blank and locked together.

Thereafter the positive positioning of the blank is obtained in co-operation with stripping pawls 40. In devices hitherto known where it has been necessary to force the blank between the spring-pressed jaws of a gripper-finger, the wear upon such jaws has been excessive whenever the spring pressure has been made sufficient to insure an effective gripping of the blanks. According to the present invention,

the wear upon such jaws has been excessive whenever the spring pressure has been made sufficient to insure an effective gripping of the blanks. According to the present invention,

the blank is freely engaged by the jaws without any appreciable wear, and subsequently subjected to a powerful gripping action. The jaw faces are preferably made smooth so that the blanks will not be marred, even though subjected to considerable gripping pressure, and it will be seen that the design of the upper and lower finger-like members 5, 6 is such that a certain amount of resiliency is provided in them so that the pressure on the jaws will never be excessive, and this is true even if two blanks should accidentally be gripped at once. In such a case, unless a certain resiliency in the gripper-fingers were provided, a breakage would probably result.

The pair of feed bars 2 are preferably actuated by a crank and connecting rod arrangement illustrated in Fig. 7. At the upper end of a vertical shaft 45 is keyed a rotating head 46, in the upper face of which is fastened a crank pin 47. This pin is held in position by means of a set screw 48. A connecting rod 49 provided with an internally-threaded, length-adjusting sleeve 50 transmits motion from the said crank pin 47 to a slide or cross-head 51. The rotation of head 46 causes the slide or cross-head to reciprocate in the guideway 52 formed in the table 1 (see Fig. 10). The cross-head carries a pair of upwardly-extending arms 53 which are fastened by the cross-bar 53' to the pair of feed bars 2, and in this manner the required reciprocating motion of the feed bars is obtained.

The position of the feed bars which carry the gripper-fingers may be adjusted with respect to the stripping pawls hereinbefore described by varying the length of connecting rod 49, the threaded sleeve or turnbuckle 50 being provided for this purpose. At either end of the turnbuckle a lock nut 53" is provided to maintain it in the desired adjustment.

The improved blank-holding device whereby the blanks are clamped securely in position at one side of the body-forming horn 55 is best illustrated in Figs. 7, 8 and 9. This device comprises a radially slideable key 56, the lower surface of which is inclined to co-operate with a wedge 57 so that the key is moved by a reciprocation of such wedge, upwardly upon a movement to the right, and downwardly upon the reverse movement, the co-operating inclined surfaces of the wedge and key imparting a perfectly true vertical movement to the latter. The upper or outer surface of key 56 is rounded so that in its outermost position, shown in Fig. 9, the surface of the key forms a smooth continuation of the rounding surface of horn 55 about which the blank is wrapped to form the can body. Immediately above the key and parallel therewith, is a straight bar 58 which is mounted in a downwardly-projecting portion 59 of the frame of the body-making ma-

chine, such portion being known as the wing bracket, as it is upon such bracket that the wings which bend the blank around the horn are mounted.

When the key 56 is forced upwardly to its outer position it approaches bar 58 sufficiently close to effectively clamp the blank which has been fed therebetween. The timing of the mechanism which actuates the wedge 57 is such that while the blank is being fed by the gripper-fingers onto the horn and until the blank has been accurately positioned by stripping pawls or some similar arrangement, the wedge does not produce any real clamping action. The bar 58 which co-operates with key 56, is at all times preferably urged gently towards the latter by springs 59; so that the blank, as it is fed onto the horn, will be lightly held between the said key and bar. This arrangement does not, however, result in a sufficient frictional effect upon the blank to strip it from the gripper-fingers upon the rearward movement of the feed bars. It will be observed that the nose portions of the bar and key between which the blank is ultimately clamped are rounded, as shown, to provide smooth guiding surfaces, which lead the entering blank between them, even though the blank be somewhat bent out of proper alignment. After a blank has been accurately positioned over the horn, it is clamped longitudinally along its center line, and such clamping action is not due to the light pressure of springs 59 but is caused by the full force applied by wedge 57, because when the wedging action takes place, the upper bar 58 of the clamp rests firmly against the wing bracket itself and is no longer resiliently supported.

The wedge 57 is reciprocated by a cam device, as will presently be explained, but such actuation preferably takes place through a somewhat resilient transmission device such as is provided by the spring link 60. This link is pivotally connected between a rocker arm 61 and the clamp-actuating wedge 57, and comprises a simple plunger member 62 which slides in a socket member 63, a spring 64 being interposed between shoulders on the two members, so that forces tending to move the wedge toward the right to effect the clamping of the blank will be transmitted through the said spring. The rearward movement of the wedge is effected through a simple lost motion coupling comprising a pin 65 which projects from the shoulder member 62 into slots 66 formed in the socket member 63. When the upper end of rocker arm 61 moves to the left, the said pin engages the left-hand end of slot 66 and thus effects a positive withdrawal of the clamping wedge 57. The object of providing a resilient coupling as above set forth is two-fold. It insures the proper clamping pressure upon the blank even though the parts of the

mechanism are not adjusted with great accuracy; and it also avoids the possibility of straining any portion of the mechanism in case two blanks should accidentally enter the 5 horn clamp at one time.

The rocker arm 61 is pivotally mounted at 67 upon a bracket 68 secured to the frame of the machine, and at its lower end is pivotally connected to a rod 69. This rod is made in 10 three sections, the center section of which is screwed into the two oppositely-threaded end portions 70, 71, the length of the rod being thus readily adjustable by rotating the central section 69. The adjustment of the rod 15 is maintained when once effected by tightening lock nuts 72. By means of such an adjustment the movement of the resilient coupling 60 can be regulated so as to impart any desired pressure to the clamp wedge 57.

20 Rod 69 is reciprocated by a cam roller 73 which is mounted on a pin 74 which projects upwardly from the rod. The cam roller runs in a continuous cam track 75 formed in the lower face of the rotating head 46 previously 25 described. As seen in Fig. 8 (the view being taken from below), the cam track is so formed that upon a clockwise rotation of the head 46, the cam roller, in passing over the arc *a*, *b*, will move rod 69 to the 30 left, such motion effecting a movement of wedge 57 to the right so that it clamps the blank between key or spline 56 and bar 58. Thereafter, until the head has rotated through the arc *b*, *c*, the rod 69 executes a 35 further slight movement to the left and then returns, but the wedge 57 remains substantially at rest due to the lost motion permitted by the resilient coupling 60. The radius of the cam track over the arc *c*, *d* then increases, 40 so that a further rotation of the head causes the cam roller to shift rod 69 to the right, thereby releasing the wedge clamp and freeing the blank, which, at such time, has been wrapped around the horn to form a can 45 body. The continued rotation of the cam track through the arm *d*, *a* merely holds the clamp device in the released position, the radius of the cam track remaining substantially constant over such arc. This 50 completes a cycle of operation, and the cam device rotating continuously, repeats this cycle, permitting free entrance of a blank to the proper position over the horn, then clamping the blank securely in such position and 55 maintaining it thus securely clamped until the blank has been formed into a can body, the clamp then being released to permit the ejection of the can body and entrance of another blank.

60 To maintain cam roller 73 in proper co-operative relationship with cam track 75, and also to guide rod 69, a fork 76 is formed in the left-hand end member 70 of such rod, this fork slidably embracing a squared block 77, which block is in turn mounted upon the

vertical shaft 45 in such manner as to permit free rotation of the shaft therein, as by means of an anti-friction bearing 78. This arrangement permits of a perfectly free longitudinal reciprocation of rod 69 while preventing any 70 transverse displacement thereof, and for this reason, because the movement of the rod is substantially in a straight line, only a simple pin connection 79 need be provided between the rod and rocker arm 61. 75

Because of the fact that the feed bars 2 and the wedge clamping device on the horn 55 are both actuated by the rotating head 46, the former through crank 47, and the latter through the cam track 75, it will be obvious 80 that the proper coordination of such elements is readily attained. The crank pin 47 is angularly disposed with respect to the cam arc *a*, *b* in such manner that the feed bars 2 are caused, in their rearward movement, to bring the blank against pawls 40 just prior to an engagement of the horn-clamping device, sufficiently positive to strip the blank from the gripper-fingers, although at the instant the blank is stripped from the gripper-fingers by the action of the pawls hereinbefore set forth, the horn clamp has produced sufficient pressure to insure against accidental displacement of the blank when released from the gripper-fingers. 95

As is usual in can body-making machines the horn 55 is also transversely expandable, being made in three transverse sections. The center section 55 is flanked respectively on the left and right by side sections 80, 81, 100 which are pivotally mounted toward their upper edges upon cylindrical bearing members 82 projecting from the center section. Longitudinally within the said center section 55, a plunger 83 is adapted to slide, and the head of this plunger is provided with opposed wedging surfaces 84 which act upon the hinged side members 80, 81 of the horn to swing them outwardly upon a forward movement of the plunger (to the right in Fig. 7). The plunger carrying opposed wedges 84 is driven forwardly by a vertically reciprocating slide 85 having at its upper end an inclined surface 86, which engages the similarly inclined surface 87 at the left-hand end of plunger 83. The plunger is moved rearwardly by a spring 88 when the actuating slide 85 is moved downwardly. The above-described expandible horn is old in the art and is described merely to render the 110 present disclosure more complete so that the relationship of the several co-operating parts may be better understood. 115

It is necessary that the horn be made expandible in order that the marginal hooks 120 which are formed in the can body blank may be interlocked after the blank has been bent around the horn. To permit such interlocking of the hooks, the horn is collapsed, that is, the side members 80, 81 are pressed in. 130

wardly by the action of the wrapping or bending wings which form the blank around the horn. These wings are not illustrated as their construction is well known. After the 5 hooks are interlocked the horn is expanded by the upward movement of slide 85 in the manner hereinbefore set forth, and such expansion of the horn holds the hooks in effective engagement so that they may be 10 pressed or bumped together to form the usual lock seam.

Such closure of the seam is effected by a vertically reciprocating bumper illustrated in Fig. 7 and shown more in detail in Figs. 15 11 and 12. The vertical slide 85 is also connected to such bumper device, the length of the slide being such that its inclined face 86 effects the proper interlocking of the marginal hooks formed in the blank by expanding 20 the horn to its full extent just prior to the engagement of the bumper with the seam. After the bumper has acted to seal the seam it moves downwardly, thereby drawing slide 85 to its lower position and permitting 25 the horn to collapse so that the completed can body may be readily ejected from the horn.

The completed can body is ejected from the horn in a well known manner, as shown in 30 Figs. 9, 11 and 12, by an ejector slide 89 which reciprocates in a guideway formed in the upper surface of horn 55. This slide has towards its rear end a tooth 89', which, upon a forward movement of the ejector slide, engages 35 the rear edge of the can body and pushes it off the horn. The rearwardly-extending surface of the ejector tooth 89' (the surface to the left in Fig. 11) forms a smooth incline which causes the tooth to disappear within 40 the ejector slide when such slide is drawn rearwardly underneath the new blank which has been deposited over the horn. The resilient mounting which permits tooth 89' to disappear into the slide is not illustrated as 45 this is well understood in the art and forms no part of the present invention. The ejector slide 89 is connected in through bar 53' with the feed bars 2 and reciprocates therewith, so that the ejection of the can body 50 is coincident with the introduction of a new blank above the horn 55.

The bumping device according to the present invention comprises a bumper head 90, the body portion of which is in the form of 55 a hollow cylinder 91. This cylindrical portion slides freely within a vertical guide 92 which is rigidly mounted upon the frame of the machine in any suitable manner. Above the said cylindrical portion of the 60 bumper head and preferably integral therewith, is formed a mounting 93 for the removable bumper blade 94. This blade is a heavy rectangular slab of steel having a suitably hardened face 95 which is adapted to act upon the can body hooks to press them

together to seal the seam, as hereinbefore described.

The operation of the mechanism hereinbefore described has been set forth in detail in connection with the description of the 70 several co-operating mechanisms which go to make up the complete can body-making machine, but a brief résumé of the operation will here be given. The can body blanks are fed into the machine at the left-hand end (see 75 Fig. 7) by any suitable means. The feed bars 2 are continuously reciprocated by the crank 47 and connecting rod 49 which acts upon cross-head 51 connected to the feed bars. The forward movements of the feed bars advance the blanks step by step to successive stations, where, in accordance with usual practice, the several operations of notching, hook-bending and final wrapping of the blank around the horn are performed. The 80 length of the table along which the blanks are fed may be such that certain of the steps advance a blank to an idle position where no operation is performed upon it, as is well understood. At points where it is necessary to accurately position a blank with respect to a mechanism which performs some operation upon it, positively actuated gripper devices A are employed, these gripper devices being 85 mounted upon the feed bars and controlled by stationary lugs 30, 31 which engage the gripper actuating yokes 11 respectively at the forward and rearward extremities of movement of the said gripper devices, or gripper-fingers as they are termed herein. The gripper-fingers in their forward movement permit the blanks to freely enter between their jaws 7, 8 and push the blank to advanced position, whereupon the jaws are locked by the engagement of the actuating 90 yokes 11 with lugs 31. The blank thus gripped is then pulled rearwardly until it is engaged by stripping pawls 40 which strip the blank from the gripper-fingers and thus accurately position it. The gripper-fingers, in continuing their rearward movement, pass 95 underneath the blank occupying the next station to the rear, the gripper-fingers disappearing into the recess provided in the feed bars while passing underneath such blank. 100

The last pair of gripper-fingers in the series along the feed bars move the blank over the top of the horn and accurately position it with respect to the horn through the action of stripping pawls 40, as previously described. The blank thus positioned is then securely clamped on the horn by the advance of clamping wedge 57 which presses upward the clamping key 56 against the bar 58, between which key and bar the blank is disposed. The blank thus clamped in position over the horn is wrapped about the horn in a well known manner and its marginal hooks interlocked, whereupon the hooks are bumped together to form a secured lock seam by the 110 115 120 125 130

- action of any suitable form of bumper acting in timed relationship with the mechanism hereinbefore described. The completed can body is ejected from the horn in a well known manner by a reciprocating ejection slide 89 which is connected to the feed bars, so that as the can body is pushed off the horn, a new blank is advanced into position above the horn.
- 10 While my invention in its preferred embodiment has been hereinbefore described and illustrated, it will be understood that the invention is not limited to such disclosures but may be otherwise variously modified and embodied without departing from the spirit thereof, as set forth in the following claims.

What I claim is:

1. In a can body-making machine, a blank gripping device comprising a pair of jaws, a jaw-actuating member adapted to relatively move said jaws positively together, a feed member on which said jaws are mounted, and a part of said machine with respect to which said feed member moves, said part co-operating with said jaw-actuating member to effect a positive closure or gripping action of the jaws upon a predetermined movement of said feed member.
2. In a can body-making machine, a blank gripping device comprising a pair of jaws, a jaw-actuating member adapted to positively move said jaws nearer together, a feed bar on which said jaws are mounted, and a trip adapted to change the position of said jaw-actuating member upon a predetermined advance of said feed bar whereby to cause the jaws to positively grip the blank.
3. In a can body-making machine, a blank gripping device comprising a pair of jaws, a jaw actuating member adapted to positively close said jaws to grip a blank, a feed member on which said jaws are mounted, and a trip member adapted to move said jaw-actuating member after a predetermined forward blank-feeding movement of said feed member whereby said jaws are closed.
4. In a can body-making machine, a gripping device comprising a pair of jaws, a jaw-actuating member adapted in one position to exert a positive jaw closing force and in another position to release said jaws, a reciprocating feed member carrying said jaws and said actuating member, and two trip members alternately engaged by said jaw-actuating member upon opposite movements of the said feed member whereby said jaws are alternately caused to grip an object between them or to open.
5. In a can body-making machine, a gripping device comprising a pair of jaws, a spring to open said jaws, an arm pivotally connected to one of said jaws, and acting upon a cam surface associated with the other of said jaws, and trip means adapted to move said arm upon relative movement between

said jaws and said trip means, whereby the jaws will be closed to grip a piece of material between them.

6. In a can body-making machine, a blank-gripping device comprising a two-part gripper finger, the parts of said finger being pivotally connected together and pivotally mounted on a reciprocating feed bar, an arm pivoted to one of said parts, a cam surface on the other of said parts, a member on said arm adapted to cooperate with said cam surface to close or release the gripper-finger, and two stationary trips adapted to move said arm back and forth upon the opposite movements thereof due to the reciprocation of said feed bar, whereby the said gripper-finger will be alternately closed and released.

7. In a can body-making machine, a blank-positioning device comprising a pair of co-operating jaws between which a blank may be gripped, a reciprocating feed member on which said jaws are mounted, said feed member and jaws acting to propel a blank forwardly to an advanced station and then draw the blank rearwardly a relatively shorter distance, jaw-actuating means adapted in one position to exert a positive jaw closing force and in another position to release said jaws, a trip member engaging said jaw-actuating means to positively cause said jaws to grip a blank upon a forward movement of the feed member, and stripping means adapted to prevent the rearward movement of the blank beyond a predetermined point, whereby the blank is withdrawn from the said jaws upon a continued rearward movement of the feed member and accurately positioned, the said withdrawal of the blank occurring while the said jaws are being subjected to the positive jaw closing action of said actuating means.

8. The blank-positioning device according to claim 7, further characterized in that a second trip member is provided, which, upon the rearward movement of said feed member is engaged by said jaw-actuating means after the said blank has been stripped from the jaws, whereby the jaws are released, resilient means being also provided to open said jaws upon their release whereby they will be in a position to freely receive another blank.

9. The blank-positioning device according to claim 7, further characterized in that resilient means are provided tending to open the jaws, the jaws having in addition to their relative movement, a common articulation with respect to said feed member whereby they are permitted to be depressed when carried rearward under a blank, and a second spring adapted to return said jaws to normal position after they have passed out from under the said blank.

10. A blank-clamping device for holding a blank on the horn of a can body-making machine while such blank is being bent around the horn, said device comprising a

pair of relatively movable clamping members between which a blank may be clamped, one of said members forming a part of the horn around which the blank is wrapped, and 5 wedge means adapted to move the latter member toward the other member whereby a blank may be clamped in a required position with respect to said horn.

11. A blank-clamping device for holding 10 a blank on the horn of a can body-making machine, said device comprising a key disposed in the body-making horn and transversely movable with respect thereto, key-actuating means to forcibly move said key 15 outwardly, and a co-operating clamp member against which said key is adapted to act to clamp the blank in a required position with respect to said horn.

12. The clamping device according to claim 20 11, further characterized in that said key-actuating means comprises a reciprocating wedge.

13. The clamping device according to claim 25 11, further characterized in that said key is radially slidable in said horn and said co-operating clamp member is disposed with respect thereto in such position that the blank will be clamped along a plane substantially tangent to said horn.

30 14. The clamping device according to claim 11, further characterized in that said key is transversely slidable in a guideway formed in the horn, and said key-actuating means comprises a wedge longitudinally slidable in 35 said guideway.

15. In a can body-making machine a blank-clamping device comprising a stationary horn around which the blank is wrapped to form a can body, said horn having a radially expanding part, and a member against which 40 said part is adapted to expand, whereby to clamp a blank between said part and said member.

16. The clamping device according to claim 11, further characterized in that the said co-

operating clamp member is movable transversely with respect to said horn, positive stop means being provided to check its movement away from the horn whereby the blank may be positively clamped against said member upon an outward movement of the clamp key, and yielding means adapted to maintain said member in contact with the surface of a blank when said key is not in the clamping position.

17. The clamping device according to claim 10, further characterized in that yielding means are provided to maintain at least one of said members in contact with a blank which is fed between the members, whereby it will be maintained in proper relationship with the horn even when the wedge means is in a position to release the clamp.

18. The clamping device according to claim 10, further characterized in that a reciprocating driving means is provided to actuate said wedge means, there being a resilient connection between said wedge and driving means whereby the wedge is yieldingly advanced to effect an engagement of the clamping members, and a lost motion connection between said means adapted to positively move said wedge in the opposite direction upon a reverse movement of the said reciprocating driving means.

19. A can body-making machine having a reciprocating feed member on which a series of blank-moving fingers are mounted, a wedge actuated horn clamp into which the blanks are fed by the movement of said feed member, a crank adapted to reciprocate said feed member, a cam adapted to actuate said wedge to effect the clamping and release of each blank as it is delivered to the horn by said feed member, and a driving shaft upon which the said crank and cam are mounted.

In witness whereof, I have hereunto signed my name.

PETER KRUSE.
